WO	03095760 A1	11/2003

Primary Examiner — Susan Bennett Hattan*Assistant Examiner* — Camelia H Styles(74) *Attorney, Agent, or Firm* — Abel Law Group, LLP; Alexander H. Plache(57) **CLAIM**

An ornamental design for a siding panel, as shown and described.

DESCRIPTION

FIG. 1 is a front isometric view of a siding panel showing our new design;

FIG. 2 is a front elevation view for the siding panel of FIG. 1;

FIG. 3 is a rear elevation view for the siding panel of FIG. 1;

FIG. 4 is a left side elevation view for the siding panel of FIG. 1;

FIG. 5 is a right side elevation view for the siding panel of FIG. 1;

FIG. 6 is a top plan view for the siding panel of FIG. 1; and, FIG. 7 is a left side elevation view for the siding panel of FIG. 1.
